FIG. 1 is a front perspective view of a combined portable electric organ, automatic record player and stand or similar article, showing my new design with the cover open;

FIG. 2 is a front elevational view with the cover closed and the stand omitted for convenience of illustration;

FIG. 3 is a left-side elevational view with the cover closed showing the loudspeaker grill, the stand being omitted for convenience of illustration; and

FIG. 4 is a right-side elevational view with the cover closed showing the record-insertion slot, the stand being omitted for convenience of illustration.

The fragmentary broken-line showing of a hand and record in FIG. 1 are for illustrative purposes only.

I claim:

The ornamental design for a combined portable electric organ, automatic record player and stand or similar article, as shown and described.
